UNITED STATES PATENT OFFICE.

PHILIPPE DE CLAMECY, OF CHARLESTOWN, MASSACHUSETTS, ASSIGNOR TO CORONA
TYPEWRITER COMPANY, INC., A CORPORATION OF NEW YORK.

TYPE-WRITING MACHINE.

1,278,873.

Specification of Letters Patent. Patented Sept. 17, 1918.

Application filed March 6, 1916, Serial No. 82,402. Renewed June 25, 1918. Serial No. 241,872.

To all whom it may concern:

Be it known that I, PHILIPPE DE CLAMECY, a citizen of the United States, and residing in Charlestown, county of Suffolk, and State of Massachusetts, have invented certain new and useful Improvements in Type-Writing Machines, of which the following is a full, clear, and exact description.

This invention relates more particularly to the key action of a front strike or other visible typewriting machine which may be made compact when not in use to adapt the same for transportation and other purposes.

One of the principal objects of the invention is to provide a small compact portable typewriter in which the keyboard is mounted upon a frame part or member which is slidably held to the main frame part or member and is movable from a normal operative or extended position to an abnormal and more compact one when not in use, and at the same time so construct the frame or support that it may form an inclosing case for the keyboard when in a compact condition, and which may be opened to adapt the typewriter keys and other parts to be readily accessible for operation in the usual way.

Another object of the invention is to provide a typewriter which is very compact when not in use and which is so constructed that it may be readily transported as a part of a person's luggage, or for other purposes.

Other objects of the invention are to provide a typewriter in which the support may be variously constructed whether as a case in which all the mechanism is mounted in order that a separate carrying case may be dispensed with, or wherein the frame may be constructed simply as a mounting for the different mechanisms so that the typewriter may be placed in a separate and independent carrying case, if desired; to provide an effective key action in which key-operated levers may have their connection maintained between said levers and the type-bars in both the operative and compact positions, and to provide type-bars having a sliding radial movement with respect to the printing point and which are operatively connected to the key-operated levers.

A further object of the invention is to provide means whereby the inclosing case may have a part thereof locked to the key-

board frame part and the case so constructed that the keyboard is entirely protected and inaccessible when not in use.

A still further object of the invention is to provide a typewriter wherein the platen carriage and the keyboard in their operative and in their compact positions are always maintained in an upright position.

With these and other objects in view, the invention will be hereinafter more particularly described with reference to the accompanying drawings, which form a part of this application, and will then be pointed out in the claims at the end of the description.

In the drawings, Figure 1 is a plan view, partly broken away, of one form of machine embodying the invention, showing certain parts of the mechanism at one end of the machine in elevation, and other parts partly in section and partly in elevation for the purpose of better illustration.

Fig. 2 is a longitudinal section of the machine, partly in elevation, showing the mechanism and keyboard in extended operative position.

Fig. 3 is a fragmentary sectional plan taken on the line III—III of Fig. 2, showing the means for guiding and holding the keyboard frame part of the main frame part of the machine in the extended and compact positions.

Fig. 4 is a vertical section taken on the line IV—IV of Fig. 2 of the parts shown in Fig. 3.

Fig. 5 is a vertical longitudinal section similar to Fig. 2, except that the parts are moved to a compact position and the case closed for transportation purposes.

Fig. 6 is a fragmentary vertical section, partly in elevation, taken on the line VI—VI of Fig. 5; and

Fig. 7 is a fragmentary vertical section on an enlarged scale, taken on the line VII—VII of Fig. 2, showing one end of the guide bar for the wire links or connections.

While the invention is shown as applied to a particular kind of typewriter in which the keyboard is mounted and connected to the type-bars in a particular way and the different mechanisms are shown of a particular construction, it will be understood that many of these parts may be changed, and that some of the parts may be dispensed

with or others substituted therefor without changing the nature or character of the invention.

The inclosing case 10 or other frame or support for the different parts of the typewriter may be variously constructed. As shown, the case or frame 10 comprises a main substantially box-like frame part 11, having a base 11^a, a rear wall 12 a partially open front wall 12^a and side walls 13. The base 11^a may be continuous or may have two offset parts 13^a and 14, as shown in the drawings, said offset parts being provided with the usual supporting rubber feet 15, if desired. A top or cover member 16, is hinged at 17 to the upper part of the rear wall 12, and at the end opposite the hinge 16 of said cover member or top 16 is a front plate or member 18. This member 18 is hinged at the forward edge of the top 16, and is adapted to inclose the open front or space 19 of the main part, member or section 11. At the front portion of the main frame part is a keyboard member or frame part 20. This frame part 20 is slidably held to move horizontally within the main member 11 from a normal operative and extended position, as shown in Fig. 2, to an abnormal compact one, as shown in Fig. 5. The frame part of member 20 may have a substantially box-like form of considerable less height and length than the main frame part 11, and said frame part 20 has a base 21 on which may be supporting feet 22, a front wall 23 having an extended portion, as 24, by which the frame part 21 may be moved inwardly and outwardly and a top portion or plate 25. The base 21 of the frame part 20 is adapted to slide forwardly and rearwardly on the offset base part 14 and has its side walls 26 provided with slots 27. These slots 27 are each adapted to be engaged by the shank 28 of a pin or bolt 29, and engaging the threaded end of the shank 28 of each bolt is a thumb nut 30. The shank of the bolt 29 has a square portion to fit the slot 27 and forms a bearing portion and guide for the sides of the frame part 20 during its horizontal sliding movement. Each bolt has an enlarged head 31 so that by tightening the thumb nuts 30 at each side of the machine the extensible and slidable frame part 20 may be held either in its extended normal position or in its compact abnormal position. The front plate 18 of the inclosing case is adapted to rest against the upper surface of the top 25 of the frame part 20 when in a compact condition, and mounted upon the part 18 is a lock 32, as for example a lock such as is employed on desks and which is accessible by a key through an opening or keyhole 33, whereby the tumblers of the lock may be disengaged from or made to engage a slot 34 or other holding means in the top 25 of the frame part 20 to lock said frame part against access except by means of the key. The front part 18 may be also provided with a handle, as 35, for carrying purposes, and at the rear portion the case may have end pieces, as 36, to adapt the platen carriage, as will be presently described, to have free movement transversely of the machine when in use. The side or end pieces or members 36 are hinged to the rear wall 12 and are adapted to inclose the cutaway portions 37 of the side walls of the main frame part 11. The side pieces 36 have beaded or rabbeted edges and the top member 16 may also be provided with a rabbeted or beaded edge so as to lock the end pieces or members 36 in a closed position when in the position shown in Fig. 5.

On the frame part 20 is mounted the keyboard 38. The keyboard may be of the usual standard or universal kind wherein a plurality of banks or groups of keys are arranged each operating individual type, such banks being in three or more sets, according to the number of printing characters, and whether or not a single case or double case shift is employed. The keys 39 are each arranged upon a vertically movable stem or rod 40. Each stem 40 is guided in a bushing or tubular part 41 extending upwardly from the top 25 of the keyboard frame part 20, and at the lower end of each stem 40 is a yoke or head 42 to which is pivotally connected the arm 43 of a bell-crank lever 44. The bell-crank lever 44 is pivoted at 45 to a lug or bracket 46 extending inwardly from the frame part 20, said part 46 extending inwardly from the top 25 for two banks or rows of key-operated levers and from the front plate 23 of the frame part 20 for the third row of key-operated levers. The key-operated levers 44 have a pin-and-slot connection with the stems 40 and under each head 42 is a rubber or other strip 47 to take the shock due to the return movement of the rods 40. The arms 48 of the key-operated bell-crank levers are connected to springs 49, there being a spring for each lever and each spring being connected at one end to a part of the frame part 20 and at its other end to one of said levers. A link or connection 50 extends from each key-operated lever and has one end held to the short arm 51 of a lever 52. The links or connections 50 may be of wire, as piano wire, or of any other desired form, and is adapted when a key is depressed to force the upper arm 53 of one of the levers 52 inwardly. The levers 52 are all mounted on a common pivot rod 54 which is curved according to the arrangement of the levers 53 and the parts actuated thereby. The arm 53 of each lever 52 is pivoted at 55 to a link 56, said link 56 being pivoted at 57 to a lug 58 of a type block or head 59. Each type block has a plurality

of characters or type 60 thereon, in this case three characters because there is double case shift, one of said characters representing the lower case type, another character the upper case type, and the third character or type, figures, punctuation marks, etc., this arrangement being varied according to the construction of the machine. The type heads or blocks 59 are held to bars 61. Each bar 10 61 is guided to slide in a bearing 62 and is normally forced in one direction by a spring 63, one end of which is held to the forward end of said bar and the other end to a part 15 of the main casing or frame. The bars 61 are held in slots and over the bars is a finishing and a retaining plate 64. The bars 61 are arranged in a curved path so that as they are propelled or forced inwardly they will move toward the printing point to impress a character upon the work held upon the platen 65. The bars 61 are thus substantially radially arranged with respect to the printing point so that all the type of all 20 the bars as each one is forced inwardly through the movement of the levers 52, links 56 and bars 61 on the depression of the keys 39 will strike at the same point on the work sheet. This arrangement of the type-bars is not broadly new. Instead of the type-bars having a horizontal sliding movement 25 they may have an upward and rearward movement as is common in most standard visible writing machines.

The banks or groups of keys 39 and the 30 bell-crank levers 44 all move bodily with the frame part 20 toward or away from the type-bars and the platen carriage 65 and during such movement said banks of keys and levers maintain a fixed relation with respect to each other, thus adapting the keyboard as a unit to be moved into the main frame member to make the machine compact or to be moved to an extended operative position at the will of the operator.

45 The platen carriage 65 has a platen 66 mounted upon end pieces of the carriage in the usual or in any preferred way. The carriage has a base 67 which has tongues or is otherwise constructed to move transversely 50 of the machine on the carriage bed 68. The carriage bed is held to move vertically at its ends, as will be presently described. The platen carriage may have the usual parts mounted thereon which coöperate with the platen, such as line-spacing mechanism, ribbon-vibrating mechanism, and other features usually employed in connection with type-writing machines, but such parts are not shown or described in detail, as they form 55 no part of the present invention, said parts being of any suitable or preferred construction.

The links 50 are guided in a transversely extending bar 69, there being an aperture in 60 said bar for each link so that the links are

properly held spaced apart. The bar 69 is held to one end of links 70 and these links at their other ends are pivotally held at 71 to the sides of the frame part 20. The ends of the bar 69 are guided in slots 72 of arms 70 73. These arms 73 are located on opposite sides of the machine and are pivotally held at 74 to lugs 75 extending upwardly from the part 14 of the main frame part 11. The upper ends of the arms 73 are pivoted to 75 links or connecting rods 76 and these links 76 are pivoted at their inner ends to arms 77. The arms 77 are held to studs and on said studs are eccentrics 78 so that as the links 76 are forced inward the arms or cranks 77 80 will rotate the eccentrics 78. In the compact position of the parts as shown in Fig. 5, the printing point of the platen is below the plane of travel of the lower case type on the type heads or blocks. When the keyboard frame part 20 is moved outwardly to a normal operative position, the transverse bar 69 by reason of its connection with the links 70 will force the arms 73 downwardly 85 from the position shown in Fig. 5 to that shown in Fig. 2. This downward movement of the arms 73 will force the links 76 forwardly and such forward movement of said links will rotate the eccentrics and this will elevate the carriage and platen to its normal 90 operative position wherein the printing point of the platen is in a direct line with the travel or movement of the lower type character of the type-bars. In this position the platen may be shifted for the different 95 type characters in any suitable way and may be restored to its normal position either by gravity or by spring or springs, not shown, for that purpose. During the compact movement when the keyboard frame 20 is moved inwardly within the case such movement will 100 elevate the bar 69 by reason of the link connections 70, and this will raise the arms 73 and force the links or arms 76 inwardly thereby rotating the eccentrics 78 which will 105 permit an abnormal movement of the carriage and platen allowing the same to drop below the path of the type to an inoperative position. During this compact movement the wire link connections are raised by the 110 bar 69 and are maintained in their proper relation by said bar and without liability of becoming entangled. A connection is thus always maintained between the key-operated levers and the type-bars, and during the extended and compact movement of the keyboard the normal and abnormal position of the platen and carriage is automatically effected through the action of the eccentrics 78 and the connection between said eccentrics and the keyboard frame part 20 as 115 already described.

The drawings show a particular form of escapement mechanism for controlling the letter-feed movement of the platen carriage, 120

also ribbon mechanism, and means whereby the platen carriage may be shifted in a vertical direction to adapt the type-bars to have a plurality of type thereon. These features form no part of the present invention but are claimed in other pending applications filed by me.

From the foregoing it will be apparent that a simple and efficient machine is provided wherein a keyboard frame part is slidably held to move within the main frame part, that the frame parts may be made to provide an inclosing casing or said frame parts may be constructed on the lines of the usual typewriter frame adapted to be placed in a separate carrying case or to be used independently of said case, that means are provided whereby the platen carriage may be given an abnormal movement to make the machine more compact; that an effective key-action is provided whereby a positive connection may be always maintained between the type-bars and the key-operated levers both in the normal operative position and in the compact position of the parts, that the key-action is such and the type-bars are held and travel in such a way that less noise takes place during the printing operation than is the case with the usual rearwardly and upwardly moving type-bars; that means are provided whereby the normal position of the platen carriage and the abnormal position thereof is obtained automatically during the extension and compact movement of the keyboard frame part; that means are provided whereby a wire or other flexible connection may be used between the keys and the type-bars and such flexible connection controlled and prevented from becoming entangled with each other; and that said machine is simple in construction, effective in use and may be readily made and assembled.

Having thus described my invention, what I claim as new and desire to secure by Letters Patent, is:—

1. In a typewriting machine, the combination of a support, a carriage, type-bars carrying a plurality of type held on said support, a lever operatively connected to each type bar, a keyboard frame part slidably held to said support to move relatively thereto from an operative position to a more compact one, a keyboard including key-operated levers mounted upon said frame part, and a flexible connection between the key-operated levers and the first-mentioned levers.

2. In a typewriting machine, the combination of a support, a carriage, type-bars carrying a plurality of type, a lever operatively connected to each type-bar, a keyboard frame part slidably held to said support to move relatively thereto from an operative position to a more compact one, a

keyboard including key-operated levers mounted upon said frame part operatively connected to said first-mentioned levers, and a flexible connection between the key-operated levers and the first-mentioned levers. 70

3. In a typewriting machine, the combination of a main frame part, a keyboard frame part held to move relatively thereto to and from a compact position, a platen carriage, type-bars, a bar connected to the keyboard frame part, means whereby said bar may be caused to move upwardly during one movement of the keyboard frame part and downwardly during another movement thereof, key-operated levers, levers operatively connected to the type-bars, and flexible connections between the key-operated levers and the type-bar operating levers, said flexible connections being guided and spaced apart in said upwardly and downwardly moving bar. 80

4. In a typewriting machine, the combination of a main frame part, a keyboard frame part held to slide horizontally relatively thereto to and from a compact position, a platen carriage, type-bars, a transversely extending bar connected to the keyboard frame part, means whereby said bar may be caused to move upwardly during one movement of the keyboard frame part and downwardly during another movement thereof, key-operated levers, a lever operatively connected to the type-bars, and flexible wire connections between the key-operated levers and the type-bar operating levers, said flexible connections being guided and spaced apart in said upwardly and downwardly moving bar. 90

5. In a front-strike typewriting machine, the combination of a main frame part, a keyboard frame part held to slide horizontally relatively thereto to a compact position within the main frame part, a platen carriage, type, a transversely extending bar, links connecting said bar to the keyboard frame part, pivotally held arms whereby said bar may be caused to move upwardly during one movement of the keyboard frame part and downwardly during another movement thereof, key-operated levers, levers operatively connected to move the type, and flexible connections between the key-operated levers and the type-bar operating levers, said flexible connections being guided and spaced apart in said upwardly and downwardly moving bar and adapted to have the slack thereof taken care of by the movement of said bar. 105

6. In a typewriting machine, the combination of a frame, a platen carriage, horizontally movable type, a transversely extending bar, means whereby said bar may be caused to move upwardly and downwardly, key-operated levers, levers operatively connected to the type, and flexible connections between the 110

key-operated levers and the type operating levers, said flexible connections being guided and spaced apart in said upwardly and downwardly moving bar.

- 5 7. In a typewriting machine, the combination of a frame, a platen carriage, slidably held type bars, a lever operatively connected to each type bar, key-operated levers movable bodily toward said first-mentioned 10 levers from a normal operative position to a more compact position, and flexible wire links connecting the key-operated levers with the type bar operating levers. 75
- 15 8. In a typewriting machine, the combination of a frame, a platen carriage, slidably held type bars, a lever operatively connected to each type bar, key-operated levers movable bodily toward said first-mentioned levers from a normal operative position to a 20 more compact position, flexible connections between the key-operated levers and type bar operating levers, and means for automatically taking up the slack in said connections when the key-operated levers are 25 moved to compact position. 85
- 30 9. In a typewriting machine, the combination of a frame, a platen carriage, slidably held type bars, a lever operatively connected to each type bar, key-operated levers movable bodily toward said first-mentioned levers from a normal operative position to a more compact position, flexible connections between the key-operated levers and type bar operating levers, means for holding said 35 flexible connections in spaced relation, and means for shifting said spacing means to take up the slack in said connections when the key-operated levers are moved to compact position. 95
- 40 10. In a typewriting machine, the combination of a frame, type bars mounted thereon, levers mounted on the frame and operatively connected with the type bars, a keyboard support slidably held to the 45 frame, vertically movable key-operated rods mounted on the support and movable therewith from a normal operative position into more compact relation with the type bars, bell-crank levers mounted on the support 50 and operatively connected with the key-operated rods, springs normally forcing the bell-crank levers in one direction, and collapsible constantly-maintained operating connections between the bell-crank levers 55 and type bar operating levers. 100
- 60 11. In a typewriting machine, the combination of a frame, type bars slidably mounted in the frame, a keyboard support slidably held to the frame and movable from 65 a normal operative position to a more compact position within the frame, key-operated levers mounted on said support in banks having a fixed relation to each other, and flexible connections between the key-operated levers and type bars. 110
12. In a typewriting machine, a frame having relatively slidable members, horizontally slidable type bars mounted on one member, a keyboard having vertically movable key-supporting rods and bell-crank 70 levers operated by said rods, all mounted on the other frame member, vertically arranged levers connected to the type bars, and flexible connections between the vertically arranged levers and the bell-crank 75 levers. 125
13. In a typewriting machine, the combination of a frame comprising relatively movable parts, horizontally slidable type-bars mounted on one of said parts, key-operated levers mounted on another of said parts and movable therewith from a normal operative position to a more compact position beneath the type-bars, and collapsible constantly-maintained connections between the key-operated levers and said type-bars adapted to impart a sliding printing movement to said type-bars. 80
14. In a typewriting machine, the combination of a compactible frame comprising relatively slidable parts, horizontally slid- 85 able type-bars mounted on one of said parts to slide toward and from printing position, vertically movable key-operated rods mounted on another of said frame parts and movable therewith from a normal operative position to a more compact position beneath the type-bars, bell-crank levers mounted on the frame part supporting the key-operated rods and operatively connected to said rods, and 90 collapsible constantly-maintained operating connections between the bell-crank levers and the type-bars. 95
15. In a typewriting machine, the combination of a main frame part, horizontally slidable type-bars mounted thereon, a platen carriage mounted on said main frame part, vertically extending levers pivotally mounted on the main frame part and operatively connected at their upper ends to slide the type-bars toward and from printing position, a horizontally-slidable key-board support held to the main frame part, vertically movable key-operated rods mounted on the key-board support and movable therewith from a normal operative position to a more compact position beneath the type-bars, bell-crank levers mounted on the support and operatively connected to the key-operated rods, and collapsible constantly-maintained 110 operating connections between the bell-crank levers and the lower ends of said vertically extending pivoted levers. 115
16. In a typewriting machine, the combination of a frame, a platen, a platen carriage mounted on the frame, type-bars slidably supported in the frame to move horizontally toward and from the platen, vertically extending levers pivotally supported intermediate their ends in the frame and 120 130

- 6 operatively connected at their upper ends to actuate the type-bars, vertically movable key-operated plungers mounted on the frame, bell-crank levers pivotally mounted in the 5 frame and operatively connected with said key-operated plungers, and links connecting said bell-crank levers with the lower ends of said type-bar actuating levers.
17. In a typewriting machine, the combination of a frame, a platen, a platen carriage 10 mounted on the frame, type bars slidably supported in the frame to move horizontally toward and from the platen, springs connected to the frame and type-bars for normally 15 retracting the type-bars from the platen, vertically extending levers pivotally supported intermediate their ends in the frame, links extending fore and aft of the frame and operatively connecting the upper ends 20 of said levers with the type-bars, key-operated plungers mounted in the frame, links connected at their rear ends with the lower ends of said levers, and bell-crank levers connecting the forward ends of said links 25 with said key-operated plungers.
18. In a compactible typewriting machine, the combination of a frame comprising relatively slidable horizontally compactible parts, a platen carriage, type-bars mounted 30 on one of said parts to slide horizontally toward and from the printing point, key-operated plungers mounted on another of said parts, constantly maintained connections between the type-bars and key-operated plungers embodying flexible links, and means for 35 automatically taking up slack in said flexible links when the frame parts are compacted.
19. In a typewriting machine, the combination of a frame comprising relatively slid- 40 able horizontally compactible parts, type-bars mounted on one of said parts to move horizontally toward and from the printing point, key-operated plungers mounted on another of said frame parts and movable therewith from a normal operative position to a more compact position beneath the type-bars, collapsible constantly-maintained operating connections between said key-operated plungers and type-bars embodying flexible links, 45 and means for automatically taking up slack in said links when the frame parts are compacted.
20. In a typewriting machine, the combination of a collapsible frame comprising 50 relatively shiftable parts, type-bars slidably mounted on one of said parts, levers pivotally mounted on the type-bar-supporting part and operatively connected to reciprocate the type-bars toward and from the 55 printing point, key-operated plungers mounted on another of said frame parts and movable therewith from a normal operative position to a more compact position beneath the type-bars, bell-crank levers mounted on 60 said plunger-supporting part and operatively connected with said key-operated plungers, flexible links operatively connecting said bell-crank levers with said type-bar-reciprocating levers, and means for automatically 65 taking up slack in said flexible links when the frame parts are shifted into compacted position.

This specification signed this 2d day of March, A. D. 1916.

PHILIPPE DE CLAMECY.
